TYPEWRITER, TYPEWRITER CALCULATING
MACHINE, AND THE LIKE

Robert Anschütz, Zella-Mehlis, Germany, assignor to Mercedes Büromaschinen-Werke Aktiengesellschaft, Benshausen, Thuringia, Germany

Application August 2, 1934, Serial No. 738,129
In Germany August 16, 1933

14 Claims. (Cl. 197—82)

The invention relates to a typewriter, typewriting-calculating machine, calculating machine or the like, having a spring urged carriage controlled by an escapement.

As known, typewriting-calculating machines in most cases are provided with very long paper carriages in order to comply with book-keeping requirements. Although these long paper carriages in themselves are of great deadweight, this is increased in a substantial manner by the totalizers attached to them.

Now in order that the carriage draw-spring has the necessary energy in the left-hand position of the carriage for the advance of the same, it must be heavily tensioned initially, whereby the difference in the tractive force of the spring occasioned by the long carriage path works out still more unfavourably.

Accordingly, a great and non-uniform pressure acts throughout on the loose dog of the escapement mechanism. Since this is released through the striking type lever, so the great and non-uniform force of the draw-spring works out unfavourably on the force of the impact of the type lever, i. e. the type impression appears sometimes to be strong and sometimes weak and consequently the type print acquires a very non-uniform disturbed appearance.

This drawback is noticeable especially in machines wherein the type lever is thrown by power drive against the platen and in the last part of its striking movement, it is moved against the platen only by the force imparted to it by means of the power drive. However, in the last part of the striking movement of the type lever, it draws the loose dog out of the escapement wheel bearing thereon with high friction, differing in dependence upon the various positions of the carriage whereby the striking movement of the type lever is greatly impeded.

This disadvantage is now overcome, according to the invention, by providing a special mechanically actuated carriage-advance mechanism, preferably actuated by a power drive, which mechanism is controllable in dependence upon the keys controlling the escapement.

This device is also very important for typewriting-calculating machines wherein the carriage advance mechanism is controllable by separate number typing keys and number calculating keys, in dependence upon the number calculating keys. The said device ensures that during the movement of the carriage the next totalizer moves very quickly into operative position relative to the main driving wheel so that even when quick-

ly depressing several calculating keys in succession the transfer wheel of the new totalizer is already in engagement with the main driving wheel before the latter begins to rotate. This is very important for avoiding disturbances.

In the drawings one form of construction of the invention is illustrated by way of example.

Fig. 1 shows a side elevation of a typewriting-calculating machine in which the invention is incorporated.

Fig. 2 shows a plan of an arrangement according to Fig. 1, in which the upper part of the typewriting-calculating machine is imagined to be removed and only a part of the cam elements is illustrated, in order that the arrangement exposes in a better manner the details of the invention.

Fig. 3 shows a perspective illustration of the invention viewed from the left-hand front of the machine, in which the carriage rack is indicated in interrupted lines.

Fig. 4 shows a part of the carriage rack in elevation.

Fig. 5 shows a section according to the line A—A of Fig. 4.

Fig. 6 shows in perspective illustration different parts drawn asunder from one another, of the mechanism illustrated in Figure 3.

Fig. 7 shows a perspective illustration of the escapement mechanism.

Fig. 8 is a timing diagram of the operation of the mechanisms of the machine.

To the centre bridge 1a (Figs. 1 and 2) of the supporting frame 1 is fixed a supporting bridge 3 (see also Fig. 3) by means of lugs 3a and screws 4, (Figs. 1 and 2). To increase the bearing positions, two supporting angles 3b are fixed to the bridge 3. In the supports 3 and 3b, there is a shaft 5 arranged, on which a bridge 6 (Fig. 3) is pivotably mounted and through discs 7 (Figure 2) as well as collars 8 is held against lateral displacement by means of screws 9. In bosses 6b of the two arms 6a of the bridge 6, a shaft 10 is fixed by means of screws 11. On the shaft 10 there is mounted a number of rollers 12 and distance tubes 13 corresponding to the number of calculating key levers 10a. In order to prevent sagging or warping of the shaft 10, the same is guided in a third boss 6c (Figs. 2 and 3) of an arm 6d of the bridge 6. Two shouldered pins 14 are riveted into two further arms 6e of the bridge 6. On the rock shaft 15 for the case shift keys of the paper carriage, two further supporting members 17 and 18 are carried and are held against displacement, by four collars 19, provided

with screws 20. Lugs 17a and 18a of the supporting members 17 and 18 respectively are fixed by means of screws 21 (Figs. 1 and 2) to the centre bridge 1a of the supporting frame 1. In the downwardly directed leg 17b of the supporting member 17, as well as the similarly directed leg 18b of the supporting member 18, a shaft 22 is mounted. This shaft carries levers 23 and 24, which are pinned to it by means of pins 25, which pass through the bosses 23a and 24a of these levers. In the elongated holes 23b and 24b of the levers 23 and 24 respectively, the pins 14 of the arms 6e of the bridge 6 engage, and so connect the bridge 6 with the levers 23 and 24 and the shaft 22. A torsion spring 26, is arranged on the shaft 22 and on the one hand is connected to the downwardly directed leg 18b of the supporting member 18 and on the other hand engages in a hole 27a of a collar 27 screwed fast on the shaft 22 by means of the screw 28. The torsion spring 26 acts upon the shaft 22 in the direction of the arrow "a" so that by way of the parts 23, 14 and 24, the bridge 6e, 6a—18—6a, 6e, is rocked in the opposite direction of the arrow "a", whereby its rest position is defined by contact of the rollers 12 with the cams 60a to be later described. On the shaft 22, further, there is a lever 29 fixed by means of a pin 30, which passes through its boss 29a. A retaining spring 31 is screwed to the lever 29 by means of a screw 32 which spring is laid against a shouldered pin 33 riveted into the lever 29. By means of this shouldered pin 33 the rod 34 is articulately jointed by means of its lug 34a to the lever 29, whereby the spring 31 prevents the lug 34a from automatically falling off from the pin 33. The rod 34 is connected to a second rod 36 by means of headed rivets 35 which engage through slots 34c of the rod 34, so that the rods 34 and 36 are mutually displaceable. Through two springs 37 which are connected to the lugs 34d and 36b of the rods 34 and 36, the two rods act as a single rod. The object of the two springs 37 is explained hereinafter in greater detail in the description of the manner of operation of the mechanism. The rod 36 is articulately jointed by means of a headed pin 38 to an angle lever 39 and is secured from falling off by the engagement of a spring ring 40 in a ring groove of the pin 38. The angle lever 39 is pivotably mounted by means of its boss 39a on a headed screw 41, which on its part is screwed into a supporting angle 42 provided for this purpose. This supporting angle is screwed to the rear part 62 of the machine housing by means of two screws 43. An insertion and shift member 44 (Figs. 3 and 6) is rotatably mounted on a headed screw 45, which is fixed in a horizontal angled lug 39b of the angle lever 39, by means of a washer 46a and a nut 45b (Fig. 6). A spring 46 which is connected on the one hand to a spring pin 47 of the insertion member 44 and on the other hand to a spring pin 48 of the bent lug 39b of the angle lever 39, holds the insertion member in the rest position through striking of the nose 44c (Figs. 2, 3 and 6) of the insertion member 44 on the nose 42b of the angle 42a. On the insertion member 44 a shift nose 49 is pivotably mounted by means of a headed rivet 50. Arranged in a milled recess 44d (Fig. 6) of the insertion member 44 is a torsional spring 51 (Figs. 2, 3, and 6), which engages with one end in a hole 44e (Fig. 6) of the insertion member 44 and with the other end engages in a hole 49a (Fig. 6) of the shift nose 49, and which holds the shift nose in the rest position by its stop face 49b

pressing on the face 44b (Figs. 3 and 6) of the insertion member 44. The angle 42a, already mentioned, serves as stop and guide for the insertion member 44, and is screwed to the supporting angle 42 by means of screws 54. The shift nose 49 is capable of moving into engagement with the locking teeth 56 (Figs. 4 and 5) milled in the known carriage rack 55 (Figs. 2, 3 and 4) of the carriage, whereby the carriage is positively shifted on operation of the calculating keys 57 by means of the cams 60a.

The manner of operation of the mechanism is as follows:—

By a motor, which is not illustrated, a shaft 59 (Figs. 2 and 3) is rotated by way of a wheel 15 58 constantly in the arrow direction a1 (Fig. 3). Since the mechanisms hereinafter described are referred to in detail in the U. S. patent application Ser. No. 406,475, these at this point shall only be mentioned briefly.

Now, if a calculating key 57 is struck, so the coupling pawl 59a, displaceably mounted on the cam 60 is released and under the action of its spring 59c, (Figs. 1 and 3) is displaced in the arrow direction b, whereby the nose 59b of the coupling pawl 59a, enters into the tooth space lying opposite to it of the locking wheel 61 associated with this pawl and fixed on the shaft 59. Consequently, the cam 60 which actuates a differential member Z (Fig. 1) participates in the rotation of the shaft 59 in the arrow direction a1.

Hereby first at 40 degrees (Fig. 8) follows the unlocking of the mechanisms while at the next 80 degrees, that is to say, from 40 to 120 degrees, 35 the differential member Z is drawn down by a tension spring 62 (Fig. 1) associated with it, and the key lever 63 is actuated by the projection 64 (Fig. 1) of the differential member Z. The key lever brings by way of a lever 65, a draw-lever 40 66 into driving connection with the cam shaft N, whereby the type lever 67 is caused at the next 150 degrees, that is to say, from 120 to 270 degrees (Fig. 8) to strike by way of the intermediate lever 68 (Fig. 1). The type lever 67 thereby 45 actuates through its projection 67a the dog rocker 72c (Fig. 7) carrying the loose dog 72a and the fixed dog 72b, by way of the parts 88, 78, 71 and 72, whereby the escapement wheel 72d and pinion 55A engaging the rack 55 are 50 released at the next 35 degrees, that is to say, from 255 to 290 degrees (Fig. 8). Consequently, the paper carriage W under the pull of the usual carriage draw spring (not shown) arranged in a housing 55c at the rear wall of the machine 55 frame, is moved through one step to the left through the intermediary of the part 55B attached to the side wall Ww of the paper carriage W. Since, however, the spring pull, especially with long carriages, is too sluggish, and in consequence of the great difference in the tension of the spring resulting from the long carriage travel is too non-uniform, according to the invention, the carriage is positively moved forward in the following manner.

The cam 60a (Figs. 1 to 3) which is rigidly connected with the cam 60, likewise participates in the rotation of the shaft 59 in the arrow direction a1, whereby the projection 60b (Figs. 1 and 3) of the cam 60a, acts at the next 110 degrees, that is to say, from 180 to 290 degrees (Fig. 8) on its associated roller 12 of the bridge 6e, 6a—18—6a, 6e, and swings the same in the arrow direction a1.

Now, since the levers 23 and 24 fixed on the 75

shaft 22, are connected through the slots 23b and 24b by way of the pins 14 with the arms 6e (Figs. 1 to 3) of the bridge, the levers 23 and 24, together with the shaft 22, are moved in the 5 arrow direction b and simultaneously the lever 29 likewise fixed on the shaft 22 in the arrow direction d (Figures 1 and 3). The rod 34 engaging with the pin 33 of the lever 29 and held by the spring 31 is now drawn down and by means of 10 the springs 37 takes the rod 36 along with it in the arrow direction e (Figs. 1 and 3). Accordingly, the angle lever 39 is swung in the arrow direction g, whereby the insertion member 44 and the shift nose 49 which together are rotat- 15 ably mounted on the horizontal bent lug 39b of the angle lever 39, are simultaneously moved in the arrow direction g (Fig. 3). Since in this movement the inclined face 44a of the part 44 slides off from the nose 42b of the angle 42a, a 20 movement of the parts 44 and 49 occurs in the arrow direction h (Figs. 2 and 3). Therefore in the corresponding co-operation of the movements in the arrow direction g and h (Fig. 3) the shift tooth 49 first is engaged with one of the 25 teeth 56 of the rack 55 and simultaneously shifted forward, so that the carriage is carried along with it in the carriage step direction. By means of the torsion spring 26 on the shaft 22, which on the one hand is connected to the hole 27a of the 30 collar 27 fixed on the shaft 22 and on the other hand is connected to the downwardly directed leg 18b of the support 18, all the parts of the mechanism are brought back into their rest position as soon as the projection 60b of the cam 60a has 35 released the associated roller 12 at 290 degrees (Fig. 8). In order now to avoid in this return the possibility of shocks or sticking of the shift nose 49 in the teeth 56 of the rack 55, the shift nose 49 is arranged to be rotatable in the clockwise direction, to the insertion member 44. A torsion spring 51, one end of which engages with the insertion member 44, while the other end engages with the nose 49, presses the latter with its stop face 49b against the face 44b of the 40 insertion member 44, but permits, however, through rotation in the clockwise direction a ratcheting over the teeth 56 of the carriage rack 55 under the influence of the spring 51. The two rods 34 and 36 connected together by the springs 37 and acting as a single rod, have the following 45 purpose.

The extent of the carriage step, as known, is determined by the dog tooth 72a, which engages in the shift wheel 72d. Since, now, the shift 50 nose 49 engaging in the carriage rack 55 dis- places the carriage to the left and consequently the tooth for the time being of the escapement wheel 72d bears hard on the loose dog 72a, so the form of the cams 60a must be shaped with 55 the utmost accuracy in order to correspond accurately to the stroke limited by the loose dog 72a, since otherwise considerable jamming could occur. By the arrangement of the springs 37, however, no particular attention requires to be 60 paid to the form of the cams 60a whereby the assembly of the mechanism may be simply and cheaply performed and the greatest reliability in the operation of the same is ensured.

The mechanism according to the invention can 70 also be applied to hand-driven typewriting-calculating machines. In this case the keys may act directly on the yoke 6e, 6a—10—6a, 6e, which on its part for facilitating the depression of the key can act on the carriage escapement mechanism by means of a suitable lever transmission.

Obviously the mechanism may find application in power and hand-driven typewriters or calculating machines and the like.

The usual carriage draw spring in consequence of the mechanism according to the invention can 5 be lightly tensioned, so that it is just sufficient to be able to accomplish the tabulating processes released by the usual tabulator keys. Accordingly the frictional pressure between the escapement wheel 72d and the loose dog 72a is considerably decreased so that the life of these parts is substantially increased.

I claim:—

1. In typewriters, typewriter calculating machines and the like, a carriage, a carriage escapement mechanism including a loose dog for limiting the movement of the carriage in letter spacing direction, keys for controlling the operation of said escapement mechanism, a driving shaft, means between said driving shaft and said carriage to uniformly move said carriage in letter spacing direction on operation of said keys, said means being adapted to hold said carriage against retrograde movement in the moment of limitation of its letter spacing movement by said dog, 25 and spring means normally urging said carriage against said dog for holding said carriage in position after its release by the first mentioned means.

2. In typewriters, typewriter calculating machines and the like, a carriage, a carriage escapement mechanism including a loose dog for limiting the movement of the carriage in letter spacing direction, keys, a driving shaft and a printing mechanism controlled by said driving shaft on 35 operation of said keys to control the operation of said carriage escapement mechanism, means between said driving shaft and said carriage including a pawl to uniformly move said carriage in letter spacing direction on operation of said keys, 40 said pawl being adapted to hold said carriage against retrograde movement in the moment of limitation of its letter spacing movement by said dog, and spring means normally urging said carriage against said dog for holding said carriage 45 in position after its release by said pawl.

3. In typewriters, typewriter calculating machines and the like, a carriage, a carriage escapement mechanism including a loose dog for limiting the movement of the carriage in letter spacing direction, a printing mechanism, keys, a controlling mechanism, a driving shaft for operating said controlling mechanism on operation of said keys, means between said controlling mechanism and said printing mechanism for controlling the 55 operation of the same, and means between said driving shaft and said carriage including a pawl to uniformly move said carriage in letter spacing direction on operation of said keys, said pawl being adapted to hold said carriage against retro- 60 grade movement in the moment of limitation of its letter spacing movement by said dog, and spring means urging said carriage against said dog for holding said carriage in position after its release by said pawl.

4. In typewriters, typewriter calculating machines and the like, a carriage, a carriage escapement mechanism including a loose dog for limiting the movement of the carriage in letter spacing direction, keys for controlling the operation of said escapement mechanism, a driving shaft and means between said driving shaft and said carriage to uniformly move said carriage in letter spacing direction on operation of said keys, said means being adapted to hold said car- 75

riage against retrograde movement in the moment of limitation of its letter spacing movement by said dog, and spring means normally urging said carriage against said dog for holding said carriage in position after its release by said means, and means on said driving shaft for automatically engaging and disengaging the first mentioned means with said carriage.

5. In typewriters, typewriter calculating machines and the like, a carriage, a carriage escapement mechanism including a loose dog for limiting the movement of the carriage in letter spacing direction, keys, a driving shaft, a plurality of operating cams coupled with said driving shaft on operation of said keys, and a printing mechanism controlled by said operating cams to control the operation of said carriage escapement mechanism, means between said driving shaft and said carriage including a pawl to uniformly move said carriage in letter spacing direction on operation of said keys, said pawl being adapted to hold said carriage against retrograde movement in the moment of limitation of its letter spacing movement by said dog, and spring means normally urging said carriage against said dog for holding said carriage in position after its release by said pawl, and a member common to the several operating cams controlled by said keys for operating said pawl.

20 6. In typewriters, typewriter calculating machines and the like, a carriage, a carriage escapement mechanism including a loose dog for limiting the movement of the carriage in letter spacing direction, keys for controlling the operation of said escapement mechanism, a driving shaft and shifting means between said driving shaft and said carriage including a rack on said carriage and a pawl cooperating with said rack, said pawl being adapted to engage said rack and to uniformly move said carriage in letter spacing direction on operation of said keys and hold said carriage against retrograde movement in the moment of limitation of its letter spacing movement by said dog, and spring means normally urging said carriage against said dog for holding the carriage in position after release of said rack by said pawl.

7. In typewriters, typewriter calculating machines and the like, a carriage, a carriage escapement mechanism including a loose dog for limiting the movement of the carriage in letter spacing direction, keys for controlling the operation of said escapement mechanism, a driving shaft and shifting means between the shaft and said carriage including a rack on said carriage, and a pawl cooperating with said rack, said pawl being adapted to engage said rack and to uniformly move said carriage in letter spacing direction on operation of said keys and hold said

carriage against retrograde movement in the moment of limitation of its letter spacing movement by said dog, and spring means normally urging said carriage against said dog for holding the carriage in position after release of said rack by said pawl, and means normally holding said pawl out of engagement with said rack.

8. An arrangement as claimed in claim 1, characterized in that the first mentioned means includes a member adapted to yield when the extent of movement of the first mentioned means by said driving shaft exceeds the extent of carriage movement, limited by said dog.

9. An arrangement as claimed in claim 2, characterized in that a yielding means is arranged between said pawl and said driving shaft to admit the latter to rotate when the movement of said pawl is limited by said dog.

10. An arrangement as claimed in claim 3, characterized in that a yielding means is arranged between said pawl and said driving shaft to admit the latter to rotate when the movement of said pawl is limited by said dog.

11. An arrangement as claimed in claim 2, characterized in that a plurality of cams are mounted on said drive shaft for operating the first mentioned means, one cam being associated with each key.

12. An arrangement as claimed in claim 2, characterized in that a plurality of cams are mounted on said drive shaft for operating the first mentioned means, one cam being associated with each key, said cams being loosely mounted, and means for coupling said cams with said drive shaft.

13. An arrangement as claimed in claim 2, characterized in that a plurality of cams are mounted on said drive shaft, a member common to said cams, one cam being provided for each key, and means for operatively coupling said cams with said drive shaft in dependence on the operation of said keys to cause said member to operate said connecting means.

14. In typewriters, typewriter calculating machines and the like, a carriage, a carriage escapement mechanism including a member for limiting the movement of the carriage in letter spacing direction, keys for controlling the operation of said escapement mechanism, a driving shaft, means between said driving shaft and said carriage to uniformly move the latter in letter spacing direction on the operation of said keys, said means acting to hold the carriage against movement in the moment of limitation of its letter spacing movement by said member, and means normally urging the carriage against said member.

ROBERT ANSCHÜTZ.
